COLLECTION INDICATOR

Edward M. Seliga, St. Louis, Mo.

Application June 7, 1933, Serial No. 674,707

2 Claims. (Cl. 40—70)

This invention relates to indicators, and with regard to certain more specific features, to collection indicators for use on mail boxes and the like.

5 Among the several objects of the invention may be noted the provision of a collection indicator for use on mail boxes which provides indication of the time of a next collection each time that a prior collection is made, so that the prospective sender of a letter may be advised as to whether or not the collector has passed a given box and made a collection at or near the time of the desired sending; the provision of a device of the class described which also serves as means 10 15 whereby an inspector may effect a check upon the activities of a mail collector; the provision of a device of a class described having tactal means for determining the setting; and the provision of apparatus of this class which is simple, compact and waterproof and which may be readily applied to mail boxes now carrying indicator cards. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following 20 25 30 claims.

In the accompanying drawing, in which is illustrated one of various possible embodiments of the invention,

Fig. 1 is a front elevation of a mail box showing the application of the device thereto;

Fig. 2 is an enlarged front elevation of the carrying frame for the device;

Fig. 3 is a vertical section taken on line 3—3 of Fig. 1;

40 Fig. 4 is an elevation taken from the right of Fig. 3;

Fig. 5 is a vertical section taken on line 5—5 of Fig. 3; and,

Fig. 6 is a plan view of a dial per se.

45 Similar reference characters indicate corresponding parts throughout the several views of the drawing.

It has been the custom heretofore to place upon mail boxes a card indicating the hours of collection. However, these cards are unsatisfactory in that, although they indicate the hours of collection, they do not show for a given time of collection, whether or not the collector has passed and emptied the box upon which the 50 55 card appears.

For instance, the sender of a letter may find that 10.45 P. M. is the hour of collection, but if the sender arrives at the particular box at about that hour, he is not sure whether the collector has passed or will pass, because the collector 60 may have collected from the box somewhat early or perhaps will be somewhat late. This is of importance where the sender does not wish to have a letter lie in the box, say for an overnight period and, who, if he were certain that the 65 collector had passed would drop the letter at another point. The device of the present invention indicates to the sender whether the collector has made a collection corresponding to a given hour indicated, or whether he has not. 70

It also happens that the collector, when rushed may, either with knowledge or by mistake, pass or avoid a box without making a collection. In order to detect such irregularities, it has been the practice for an inspector to wait at a given 75 box at a given hour for a suspected collector. This procedure is time consuming and uncertain.

By means of the present invention an inspector needs only examine the indicators on a route to determine the efficiency with which the collector is operating. He may also easily determine at what point in the route the collector is by merely inspecting the indicators on one or a few boxes.

Referring now more particularly to Fig. 1, 85 there is shown at numeral 1 a typical mail box having a face 3 and a side entry 4 guarded by a lock 5. Letters are deposited in the box at a slot 7 which does not permit of entry for purposes of withdrawal. Letters are removed only 90 by authorized collectors who have access through the lock 5. On the face 3 of the box is located a plate 9, against which is placed a holding frame 11. The frame 11 and plate 9 are held together and to the face 3 by means of suitable 95 machine screws 13. These may be applied from the outside of the box, as shown, or from the inside.

The frame 11 is provided with a rabbet 15 for receiving a collection indicating card 17, the 100 latter having therein an opening 19 and indicia 21, the latter being of the form now in use.

The face 3 of the box is provided with an opening 23 for accomodating a detent mechanism 25 which is attached to said plate 9 by means of 105 screws 27. Four screws 27 are used which pass through four holes in the plate 9. However, a greater number of threaded holes 29 are used for receiving the four screws 27, said holes 29 spaced at corresponding intervals in sets of four. 110

- The purpose of this is to provide additional holes by means of which fastenings may be made, should one of the screws 27 have the shank sheared off from the head portion in making a connection. Thus, the necessity for removing the sheared shank from its threaded recess is eliminated, it being only necessary to turn the detent assembly a few degrees to make a new fastening.
- 10 The screws 27 enter a stationary body portion 31. On the inside of the body portion 31 is a rotary hub 33 having a flange 34 to which is affixed a positioning pin 35 and which is adapted to receive a fastening screw 37. The flange 34 rotates within a counterbore of the body 31. A circular dial 39 made of light sheet material such as sheet metal plate or cardboard is provided with an opening 41 having a notched portion 43 for passing under the head of said screw 37, and also an opening 45 for cooperating with said pin 35 thus providing a predetermined relationship with respect to the hub 33. The opening 41 is large enough to pass over the head of screw 37 thus eliminating the necessity for entirely removing the screw 37 when making dial replacements.
- 15 On the inside of the hub 33 is affixed, by means of a screw 47, a detent cap 49 having an opening for receiving a spring 51 backed by an adjustable set screw 53. The spring presses against a detent ball 55. The ball 55 is pressed against the stationary member 31 and along its path of travel on said member 31 there are located detent recesses 57. By the resilient cooperation of the detent ball 55 with the detent recesses 57 in its path, the operator of the detent wheel 49 may positively determine by tactful means predetermined successive angular positions thereof.
- 20 The dial 39 is provided at angles corresponding to the angles between the detent recesses 57 with indicia 59 which, when the dial 39 is assembled behind the card 17, appear successively at said opening 19. The indicia 59 correspond to the hour of collection indicated on the card, as shown in the drawing. They include Sunday and holiday indicia and "a time change" indicator.
- 25 The operation of the device is as follows: Starting with the "3.15 P. M." index at the opening 19, the collector arrives at the box 1 at, say, about 3.15 P. M. He opens the lock 5 and box and empties the mail therefrom. He then, or before, reaches in to the index wheel 49 and turns it until the ball 55 falls into the next detent, reference being made to clockwise rotation, which may be done without visual attendance, the tactful sensation determining the appearance of the "4.20 P. M." index at the opening 19. The collector then withdraws his hand and locks the box at the lock 5.
- 30 It will be seen that in the first instance, the collector cannot show that he has collected mail from this box at "3.15 P. M." without resetting the device to indicate the next collection at "4.20 P. M." Thus an inspector knows from the "4.20 P. M." indication that the operator has been at the box for the "3.15 P. M." collection. If the collector should turn more than two indexes, the inspector could readily detect this from the exterior of the box by noting the discrepancy between the next collection prediction on the card and that on the dial.
- 35 In the second place, if a prospective sender of a letter approaches the box at about, say "3.16

P. M.", he notes that the next collection is at "4.20" and he is not left with any impression that there may yet be a collection within the "3.15 P. M." period.

It will be noted that the daily "P. M." collections are indicated to "10.45" and the next collection is "9.10 A. M." The "9.10 A. M." index on the dial 39 is thereby put subsequently and in order after the last "P. M." index. Thus, for week days, the cycle may continue as above described.

For Sundays and/or holidays, where different collection times are used, indexes are placed upon the dial 39, as indicated by the "9.15 P. M." index. In the present example, the last collection made at "10.45 P. M." on Saturday night or on a day before a holiday will require two detent operations to bring the dials 39 to the "9.15 P. M." setting for the next day. When collection is made on the next day, the dial is turned back to the "9.10 A. M." setting for the usual collection to be made the next day.

If the central office which determines the hours of collection to be placed upon the card 17 effects a time change without immediately 100 making a corresponding change upon the card, the collector sets the dial 39 so that the index "time change" appears in the opening 19, thereby indicating to prospective senders of mail that collections are not being made in accordance 105 with the card indication. This constitutes another one of the advantages of this device.

It will be understood that where desired a transparent sheet of isinglass or the like is inserted over the card 17. The detent mechanism is strong enough to prevent unauthorized operation through opening 19 but said sheet provides added protection.

The device is quite waterproof in view of the fact that the card 17 and dial function as 115 covers. Furthermore, the tortuous bearing between members 33, 31 and 49 deflects water.

Mail cannot be abstracted through the opening in bearing 31 even though a person should succeed in removing the shank 33 because of the 120 small size of the opening.

It is to be understood that the plate 9 may be an integral part of the face 3 of the box.

In view of the above, it will be seen that the several objects of the invention are achieved 125 and other advantageous results attained.

As many changes could be made in carrying out the above constructions without departing from the scope of the invention, it is intended that all matter contained in the above description or shown in the accompanying drawing shall be interpreted as illustrative and not in a limiting sense.

I claim:

1. In combination, a mail box having an opening for removing mail, a lock for said opening openable only by authorized persons, an indicating card on the face of said box and presented to view having indicia thereon predicting collection times, means associated with said card and operable only manually from the interior of said box and adapted to be set to indicate the next time at which a collection shall be made, and means for positively tactually determining the actual amount of indicator setting without specifically examining the same.

2. In combination, a mail box having an opening, a lock for said opening which is openable only by authorized persons, means for supporting a collection card on the face of said

box, said collection card having an opening therethrough and indicia thereon which predict times of collection, a dial behind said card and having indicia thereon indicating times of collection, and detent means operable only manually from the interior of the box and adapted to rotate said dial so as to place the indicia

thereon serially within said opening where they may be seen by the reader of the card, said card also having indicia thereon indicating time change conditions adapted to be presented by manual operation.

EDWARD M. SELIGA.
